[57] CLAIM

The ornamental design for a tray table, substantially as shown and described.

DESCRIPTION

FIG. 1 is a perspective view of a tray table showing my new design;

FIG. 2 is a top plan view thereof;

FIG. 3 is a bottom plan view thereof;

FIG. 4 is a perspective view of the tray table showing the bottom thereof;

FIG. 5 is an elevational view of one side of the tray table;

FIG. 6 is a sectional view taken along lines VI—VI of FIG. 2;

FIG. 7 is an elevational view of one end of the tray table; and

FIG. 8 is a sectional view taken along lines VIII—VIII of FIG. 2.

The opposite side and opposite end are identical to those shown in FIGS. 5 and 7, respectively.

Portions of the leg members have been broken away in FIGS. 6, 7 and 8 for convenience of illustration.
